UNITED STATES PATENT OFFICE.

PERCY M. ELLIOTT, OF CHICAGO, ILLINOIS.

DRAW-BAR SUPPORT FOR RAILWAY-CARS.

1,080,509.

Specification of Letters Patent.

Patented Dec. 2, 1913.

Application filed February 4, 1913. Serial No. 746,115.

To all whom it may concern:

Be it known that I, PERCY M. ELLIOTT, a citizen of the United States, residing at Chicago, in the county of Cook and State of Illinois, have invented certain new and useful Improvements in Draw-Bar Supports for Railway-Cars, of which the following is a specification.

My invention relates in general to rail-
road cars, and more particularly to means
for supporting and automatically centering
the draw-bars thereof.

Draw-bars of cars must have a limited lateral movement in order that the adjoining cars of a train may be connected with the necessary flexibility in passing around curves in the track. The draw-bar should, however, when uncoupled, occupy a plane alining with the longitudinal center of the car in order that the couplers may automatically interlock when adjoining cars are brought together. It is, therefore desirable that draw-bars, while having the requisite lateral play, should automatically re-
turn to a position alining with the longitudinal center of the car.

The primary object of my invention is to provide means for so supporting a draw-bar that it may move laterally in a horizontal plane and will automatically return to its normal central position when uncoupled.

A further object of my invention is to provide means for supporting and automatically centering draw-bars, which will be simple in construction, durable in use, and efficient in operation.

My invention will be more fully disclosed hereinafter with reference to the accompanying drawings, in which the same is illustrated as embodied in a convenient and practical form and in which—

Figure 1 is a longitudinal vertical section through the portions of the end of a car surrounding the draw-bar, the latter being shown in elevation; Fig. 2, an enlarged sectional view on line 2-2, Fig. 1, the buffer beam being omitted; and Fig. 3, a vertical section on line 3-3, Fig. 2.

Similar reference characters are used to designate similar parts in the several figures of the drawings.

Reference characters A' and A² designate the longitudinal center sills of a car preferably formed of channel beams arranged with their webs in vertical parallel planes and with their flanges projecting outwardly.

B designates a buffer beam at the front of a car, which is preferably reinforced by means of an angle bar b.

D designates a draw-bar, to the rear of which is connected the yoke d and at the front of which is provided a coupler C.

The parts above described do not in themselves constitute my invention, as they are well known elements in car construction. They are illustrated in order that my invention may be fully understood.

E indicates a carrier plate underlying the draw-bar D for supporting the same through engagement, and preferably located in substantially the same vertical plane as the buffer beams B. The ends of the carrier plate E may be supported in any suitable manner, as by means of inwardly extending flanges E' and E² which overlie the outwardly projecting lower flanges of the center sill channel beams A' and A².

e', e² designate bolts passing through the ends of the carrier plate and through the flanges of the channel beams, and also through the overlying inwardly extending flanges E' and E² at the ends of the carrier plate. The upper surface of the carrier plate E is concave and supports an anti-friction rolling bearing, such, for instance, as the cylindrical roller F.

G' and G² indicate flanges projecting upwardly from the lower transverse edges of the carrier plate E and forming end walls between which the rolling bearing F is confined.

H designates a saddle having upwardly projecting side flanges h', h² between which the draw-bar D is so supported as to be freely movable longitudinally with respect to the saddle to accommodate the usual reciprocating movements of the draw-bar relatively to the draft timbers of the car. Depending from the inner and outer edges of the saddle H are flanges H' and H² which overlie the upwardly projecting flanges G' and G² on the carrier plate E. The under surface of the saddle H which overlies the carrier plate E is convex and substantially parallel with the upper concave surface of the carrier plate.

The operation of my invention is as follows: The draw-bar moves inwardly and outwardly with respect to the car in its usual manner, and during such movements it slides upon the saddle H and between the upwardly projecting flanges h' and h² there-

on. The draw-bar is supported by the saddle upon the carrier plate E through the medium of the interposed rolling bearing F. The lateral movements of the draw-bar 5 are communicated to the saddle H so that it will move laterally between the center sills A', A². The lateral movements of the saddle produce a rolling movement of the bearing F between the upper surface of the carrier plate and lower surface of the saddle, so that the draw-bar is securely supported 10 without interfering with its free lateral movement between the center sill beams. Owing to the concave upper surface of the 15 carrier plate, the rolling bearing will have an upward movement when the draw-bar is swung to either side of its normal central position, so that the draw-bar will automatically be restored by gravity to its normal central position by reason of the bearing rolling to the lowest point in its concave seat in the carrier plate. By forming 20 the under surface of the saddle convex, it will be observed that the lateral movement 25 of the draw-bar to either side of its normal position will not appreciably raise the draw-bar, and hence the engagement of its coupler with the coupler on the adjoining car will be in nowise affected. The depending 30 flanges H', H² on the saddle, through their engagement with the upwardly projecting flanges G', G² on the carrier plate, serve to prevent the saddle from moving longitudinally with respect to the carrier plate, but 35 without interfering with the free lateral movement of the saddle relatively to the carrier plate.

From the foregoing description it will be observed that I have invented an improved 40 means for supporting the draw-bar of a car coupler so that it may freely move both longitudinally and transversely of the car, but will automatically return to its normal position alining with the longitudinal center of the car and thereby be in position 45 when uncoupled for the engagement with its coupler of the coupler on the adjoining car. It will be further observed that by my invention the automatic return of the draw-bar to its normal central position is affected 50 without the use of springs by the action of

gravity, without however raising or lowering the draw-bar during its lateral movements, and consequently without in anywise affecting the engagement of the coupler 55 which it supports with the coupler on the adjoining car.

I claim:

1. The combination with a draw-bar having a convex under surface movable therewith, of an underlying supporting member having a concave upper surface, and a rolling element supported on the concave surface of said member and upon which is supported the convex surface carried by the 65 draw-bar.

2. The combination with a draw-bar, of a carrier plate having a concave upper surface, a saddle in which the draw-bar is supported and having a convex under surface, 70 and a rolling element interposed between the concave surface of said plate and the convex surface of said saddle.

3. The combination with a draw-bar, of a carrier plate having a cylindrically concave upper surface, a saddle in which the draw-bar is supported and having a cylindrically convex under surface, and a bearing supported on the concave surface of said plate and upon which is supported the 75 convex surface of said saddle.

4. The combination with a car having metal beam center sills arranged with the flanges thereon projecting outwardly, of a draw-bar having a lateral plate between the 85 channel beam center sills, a carrier plate underlying the center sills and having a concave upper surface, means for securing the ends of the carrier plate to the bottom flanges of the center sills, a saddle in which 90 the draw-bar is supported and having a convex under surface, and a rolling element supported on the concave surface of the carrier plate and upon which is supported the convex surface of the saddle. 95

In testimony whereof, I have subscribed my name.

PERCY M. ELLIOTT.
